UNITED STATES PATENT OFFICE

2,156,349

HOSIERY STRETCHER

Rene Oldfield, Norristown, Pa.

Application January 25, 1937, Serial No. 122,150

2 Claims. (Cl. 223—77)

The object of the invention is broadly to provide an improved hosiery stretcher, but more particularly with relation to improved means for stretching the foot portion of a stocking, hereinafter referred to as the foot, as compared to the leg of the stocking.

It is well known that many forms of stretchers have been developed, especially for full length and half length hose of the relatively light weight types, such as are commonly worn by men and women in everyday life, but little if any attention has been given to the stretching and drying of so-called golf hose, which represents a type of relatively heavy woolen hose worn especially by men, the feet of which when wet from ordinary washing, or from rain, or snow, are very difficult to draw over the corresponding foot portion of a drier of fixed or predetermined length.

Another object has therefore been to provide an improved stretcher and drier having a foot section which can be varied in length to the desired size, at which the foot of the hose should set upon becoming finally dried, and over which foot section the hose can be completely drawn, before its length section is adjusted to the desired length, after which the leg of the hose is pulled over the corresponding section of the device.

And a further object is to provide in a device of this nature, the combination of a relatively fixed heel section, preferably rigidly attached to the leg section, a toe section preferably telescopically attached to said heel section, with means extending between and adjustably connecting said toe and heel sections in variable yet normally fixed relationship, and a member extending into said leg section, said member being manually engageable and actuatable both to force said toe section outwardly from said heel section to stretch the foot of the hose, and to secure in or release from such predetermined relationship the two foot sections of the device, all while the foot section is covered by a stocking or hose.

With the objects of the invention thus briefly stated, the invention comprises further details of construction and operation, which are herein-after fully brought out in the following description, when read in conjunction with the accompanying drawing, in which Fig. 1 is a plan view of one embodiment of the invention, showing the toe section in extended relation with respect to the heel section by means of dot-and-dash lines; Fig. 2 is a section on the line 2—2 of Fig. 1; and Fig. 3 is an enlarged detailed view, partly

in section, showing the size-adjusting mechanism.

Referring to the drawing, the embodiment of the invention here shown is represented as being made in the form of a frame, in order to attain minimum weight and also facilitate the drying of hose stretched thereon, but it is to be understood that the exact construction of the device other than the particular improvements herein-after noted, is to be left to the preference of the manufacturer.

With this understanding in mind, the device is here illustrated as comprising a leg section 1 and a foot section, which in turn is sub-divided into an instep section 2 and a toe section 3. The leg section is formed of the equivalent of spaced rods 4 and 5, having their upper ends curved towards each other and joined together at 6, and provided with suitable means 7 for hanging the device from an extraneous support, or these rods may comprise a single continuous rod or tube, as is actually shown, the opposite sides of which are maintained in fixed spaced relation by means of a transverse brace 8. The rod 5 represents the rear side of the device, as it corresponds to the rear portion of a stocking when being worn, and this rod is curved inwardly or forwardly at 9, so as to more closely approach the opposite rod 4 and thus conform to the angle portion of a hose, whence the rod 5 is curved outwardly or rearwardly away from and thence reversely toward the rod 4, to provide the curved heel portion 10 over which is intended to fit the heel portion 11 of a stocking. Below this heel portion and also below a point substantially opposite thereto, the respective rods 5 and 4 assume a parallel relation at 12 and 13 and are of tubular form, whether or not the remaining portions of said rods are tubular or solid. These parallel portions 11 and 12 comprise the foot of the device and are maintained in fixed spaced relation by means of one or more suitably positioned braces 14, as shown in both of Figs. 1 and 2.

The toe section 3 is preferably formed of a solid U-shaped rod, the opposite parallel terminal portions 15 and 16 of which are reduced in diameter so as to slidably enter the interior of the tubular foot portions 11 and 12. To the center of said toe section is rigidly secured a relatively slender bar 17, which is adapted to pass slidably through apertures 18 in the braces 14, and terminates, when said toe section is in fully retracted position, approximately adjacent to the

55

heel portion 10, where it is pivotally connected at 18 to the lower end of an adjusting bar 19, the opposite end of which latter is suitably shaped to provide a handle 20.

5 An intermediate portion of the adjusting bar 19 is provided with spaced ratchet teeth 21, the abrupt sides of which are directed upwardly, while their slanting faces are directed downwardly and are adapted to slide under and selectively engage the forward surface of a strap 22, which is of U-shaped cross section and has its sides secured to the rod 5, adjacent to the ankle portion 9 of the device. As this structure is relatively small in cross section, there 10 is preferably provided between the opposite sides of said strap 22 and adjacent to the bar 5, a pair of spaced blocks 23 or their equivalent, leaving a space 24 between them, into which space normally extends the central abruptly curved 15 portion 25 of a leaf spring, the opposite terminal portions 26 of which spring bear slidably against the adjacent side of the adjusting bar 19, in order to maintain the desired tooth 21 in engagement with the outermost portion of the strap 20 25 22, as shown in Fig. 3.

It will be noted that the rear portion of the swell comprising the heel 10, is substantially parallel with the central portion of the toe section 3. This being the case, after the toe section 30 has been shifted into fully retracted position, as shown in Fig. 1, by means of the adjusting bar 19, the particular type of relatively heavy hose mentioned has its foot portion, indicated by the dot-and-dash line 27, pulled over the toe, 35 then over the instep and finally over the heel portion of the device, with the leg portion 28 of such hose crumpled about the ankle portion 9 of the stretcher, or in other words completely covering the entire foot section of the stretcher. 40 By means of the handle 20, the bar 19 is thereupon pushed downwardly, and through the medium of the bar 16 operates to force the toe section 3 into its extended dot-and-dash position, corresponding with the proper size of foot 45 to which it is intended to have the hose set in drying. The spring 25-26 automatically functions to maintain this adjustment by keeping the proper one of the teeth 21 in engagement with the strap 22. At this point it should be noted that the longitudinal length of each of said teeth 50 may be equal to a quarter-size or half-size hose, in order to obtain accurately the desired size of the foot section.

After the hose has fully dried and set, it may 55 be withdrawn from the stretcher, without first altering the length of said foot section, or such length may first be altered by manually depressing the handle (when considered in the position shown in Fig. 1), thereby releasing the teeth 21 from engagement with the strap 22, against

the tension of the spring 25-26 and then retracting the rods 16 and 19 and toe section 3 into withdrawn position, following which the hose can be even more readily removed from the stretcher, since the extent of its frictional engagement with the foot section has been materially lessened. 5

It is understood that the invention herein described may be modified as to minor details of construction and operation, without departing from the spirit of the invention in its broadest scope, and as defined by the appended claims. 10

Having thus described my invention, what I claim as new and desire to protect by Letters Patent of the United States is:

1. A stretcher for hosiery, comprising a leg section and a foot section, said foot section comprising instep and heel portions secured to said leg section and a detachable toe section adjustably carried by the instep portion of said foot section, a rod attached to said toe section, and a manually actuatable member pivotally connected to said rod and extending into said leg section, where it is engageable when said toe and foot sections are covered by a hose, spaced 20 teeth carried by said member, a lug carried by one side of said leg section, and resilient means supported by said lug and slidably engageable with said member, to normally maintain a predetermined tooth of said member in engagement 25 with said lug, said tooth-and-lug structure being released by angularly oscillating said member about its pivotal connection with said rod, against the force of said resilient means. 30

2. A stretcher for hosiery, comprising a leg section of fixed width and a foot section, said foot section comprising instep and heel portions secured to said leg section and a detachable toe section adjustably carried by the instep portion of said foot section, a part of the rear side of said heel portion being at substantially right angles to a direct line between said heel and said toe, a rod attached to said toe section and extending into said foot section, and a manually actuatable member pivotally connected to said rod and extending at all times wholly within said leg section, where it is engageable when said toe and foot sections are covered by a hose, the foot of which hose is stretched between the end of said toe section and the rear of said heel portion, a U-shaped bracket carried by one side of said leg section, a spring positioned within said bracket, and ratchet means carried by said member and adjustably engaging said bracket under the tension of said spring bearing against said member to adjustably maintain said member, said rod and said toe section in adjustable position with respect to said foot and leg sections. 40 45 50 55 60
